CLAIM

The ornamental design for the combination letter opener and magnifying glass, as shown and described.

DESCRIPTION

FIG. 1 is a perspective view of a combination letter opener and magnifying glass in a closed configuration, showing my new design;

FIG. 2 is a perspective view thereof in the open configuration;

FIG. 3 is a front elevational view thereof in the closed configuration;

FIG. 4 is a side elevational view thereof, the side opposite being identical;

FIG. 5 is a top plan view thereof; and,

FIG. 6 is a bottom plan view thereof.
